UNITED STATES PATENT OFFICE.

JESSE A. B. SMITH, OF GLENBROOK, CONNECTICUT, ASSIGNOR TO UNDERWOOD TYPE-WRITER COMPANY, OF NEW YORK, N. Y., A CORPORATION OF DELAWARE.

TYPE-WRITING MACHINE.

1,280,885.

Specification of Letters Patent.

Patented Oct. 8, 1918.

Application filed June 21, 1916. Serial No. 105,077.

To all whom it may concern:

Be it known that I, JESSE A. B. SMITH, a citizen of the United States, residing in Glenbrook, in the county of Fairfield and State of Connecticut, have invented certain new and useful Improvements in Type-Writing Machines, of which the following is a specification.

This invention relates to sheet-collating devices for use on typewriting machines, and more particularly to devices comprising work-holding and alining studs or pins, which may be projected above the face of a sheet-collating table, to enter perforations in the work-sheets for alining or squaring them to the platen and holding them in adjusted position, which studs may be retracted after the work is adjusted. It has been found advantageous to withdraw the alining studs after the sheets have been adjusted thereon, thereby leaving an unobstructed surface for the sheets to be fed over, thus avoiding any possibility of the sheets being caught or torn by the alining studs.

A feature of the present invention relates to improved means for withdrawing the alining studs. For this purpose, the studs, which are arranged in rows adjacent the opposite side edges of the alining table, may be mounted on suitable carriers or wings hinged at the back of said table, to swing said studs through openings provided in the table, into and out of operative position. A key for controlling said studs may be attached to a rock shaft mounted on the rear side of the collating table and having suitable operating connections with the stud-carriers. Said key may be conveniently located adjacent the key which controls the usual paper-feed rolls running on the platen, thus enabling the operator, by a single movement of the hand, to operate both keys so as to move the feed rolls to operative position to hold the adjusted work-sheets and at the same time withdraw the alining studs.

A further feature of the invention relates to improved means for adjusting the alining studs to work-sheets of different widths, or to cause sheets impaled on one row of studs to register with sheets held on the other row of studs. For this purpose, the collating table may comprise overlapping or telescoping sections relatively adjustable lengthwise of the platen. Said sections may be mounted on a supporting bar, one section having a

slot-and-pin connection with said bar, permitting such adjustment. The collating table may be located at the delivery side of the platen and extend upwardly and rearwardly therefrom. The supporting bar on which the table is mounted may also carry the supports for the alining studs and the mechanism for actuating said supports. Said supporting bar may be mounted on the platen frame to swing about a pivot at one end of the platen, whereby the collating table and its appurtenances may be swung upwardly and to one side, to permit ready access to other parts of the machine.

Other features and advantages will appear hereinafter.

In the accompanying drawings,

Figure 1 is a front perspective view of the carriage of an Underwood typewriting machine with the present invention applied thereto.

Fig. 2 is a rear perspective view of the sheet-collating table, and also shows the stud-carrying wings or supports and the actuating mechanism therefor.

Fig. 3 is a part sectional elevation of the platen frame and collating table, the alining studs being shown in operative position.

Fig. 4 is a similar view, but with the alining studs withdrawn.

Fig. 5 is a part sectional plan view, showing means for operating the alining studs, the studs being in operative position.

Fig. 6 is a similar view, but with the studs withdrawn to inoperative position.

The roller platen 10 is mounted on a platen axle 11, journaled in the ends 12 and 13 of the platen frame, which also comprises an inclined paper-shelf 14 at the intake side of the platen. Type-bars 15 (Fig. 4) may be operated by the usual mechanism to cause the types thereon to print at the front face of the platen. Front and rear feed rolls 16 and 17 bear against the under side of the platen and cooperate therewith to feed the work-sheets around the lower side of the platen and upwardly past the printing line. The feed-roll shafts are mounted on levers 18, journaled on a rod 19, said levers being actuated by a rock shaft 20 having cams or flats operative when said shaft is rocked to spread the arms 21 of said levers, and thereby throw the feed rolls off the platen. A feed-roll release key 22 is connected through a link 23 to a rock arm 24 on the shaft 20.

2
whereby, when said key is depressed, the shaft 20 is rocked and the rolls 16 and 17 are moved downwardly away from the platen. The feed rolls are restored to the platen by springs (not shown) when an upward pressure is applied to the key 22.

The platen may be rotated either by the hand-wheels 25 on the platen axle, or by the usual line-spacing mechanism. The latter 10 comprises a line-spacing lever 26 operable to move rearwardly a slide bar 27 carrying a pawl to drive a line-space ratchet wheel 28 connected with the platen.

The above described parts may be of the 15 usual construction, common in commercial Underwood typewriting machines.

The sheet-collating table 30 may comprise two sections 31 and 32 relatively adjustable lengthwise of the platen, to accommodate sheets of different widths, said sections telescoping or having their inner ends overlapping at 33, the edge of the front section 32 being beveled to permit the work-sheets to lie smoothly against the table without encountering a sharp edge or corner. Said sections may be mounted on a supporting bar 35, which may be in the form of an angle bar, to which the sections 31 and 32 are secured by means of screws 36 and 37, 20 respectively. A spacing plate 38 may be interposed between the supporting bar 35 and the table section 32, to space the latter from the supporting bar and provide a space for the inner end of the section 31. To permit 25 adjustment of the section 31 lengthwise of the platen, said section is provided with longitudinal slots 39 to receive the screws 36, and the latter may be set up to clamp the section in adjusted position.

40 The collating table is mounted on the platen frame in position to extend upwardly and rearwardly from the platen, the lower edge of the table being close to the platen a short distance above the printing line. 45 The means for mounting said table comprises brackets 40 on the platen frame ends, a tie-rod 41 connecting said brackets, and a rod 42 extending between the platen frame ends. Brackets 43 supported on said rods

50 41 and 42 have forwardly-extending arms 44 on which the table-supporting bar 35 is directly mounted. The bar 35 is connected at one end by a pivot screw 45 to the adjacent bracket arm 44, and its other end 55 is provided with a hook 46 to engage a thumb screw 47 on the other arm 44. By loosening the thumb screw 47, the supporting bar 35, with the collating table and other parts mounted thereon, may be swung upwardly and to one side about the pivot 45, to permit access to other parts of the machine. The rod 41 may also form a support for tally-strip spools, when a tally-strip is used.

65 Sheet-alining and supporting studs or pins

48 are arranged in rows adjacent the outer edges of the collating table, and project upwardly or outwardly from the surface of the table to enter correspondingly positioned perforations in the work-sheets. The studs 70 48 are preferably formed with flattened heads 48a of slightly greater diameter than the perforations in the work-sheets, to prevent accidental disengagement of the sheets from the studs. These alining studs are 75 arranged to be withdrawn after a work-sheet or sheets have been arranged thereon, to permit the sheets to be fed over the surface of the table without obstruction.

To enable said studs to be withdrawn 80 to inoperative position, they are mounted on swinging supports or wings 49, said wings being mounted on the rear face of the collating table. Said wings are provided with pivot pins 50 pivoted in ears 51 on brackets 85 52 secured to the rear faces of the table sections 31 and 32. By swinging the supporting wings 49 about their pivots, the studs 48 may be projected through openings 53 in the table to the operative position shown 90 in Fig. 3, or may be withdrawn to the Fig. 4 position. The wings 49 are actuated by means of a key 54, fixed to a rock shaft 55, to which are secured rock arms 56, extending upwardly from the shaft to engage 95 notches 57 in angle brackets 58 fixed to said wings. When the key 54 is moved rearwardly, the shaft 55 is rocked, causing the rock arms 56 to swing the wings 49 rearwardly and withdraw the studs 48 from the 100 collating table.

The studs 48 may be held in operative position by holding pin 59 secured to the rock shaft 55 and seating in a recess 60 in a bracket 61 secured to the table section 32. 105 When the key 54 is operated to withdraw the studs 48, the elastic holding pin 59 is cammed outwardly, sliding along the inclined face of the recess 60 to the Fig. 6 position. The rock shaft 55 may be journaled in bearing blocks 62, mounted on the angle bar 35. One or both of the rock arms 56 may be adjustable along the rock shaft 55 to positions corresponding with the adjustment of the collating table. Said rock 115 arms may be held in adjusted position by set screws 63. By adjusting the table section 31 lengthwise of the platen, the distance between the rows of studs 48 at opposite ends of the table, may be adjusted for sheets of 120 different widths, or in which the marginal rows of perforations are at different distances apart.

The operation of the device may be as follows, when used, for example, in a bookkeeping system wherein a bill, invoice or the like, is placed on the machine, together with a record sheet, to receive typewritten entries, the record sheet being employed to receive the record copies of entries on a number of 125 130

succeeding bills or invoices. In arranging the work on the machine, the platen feed rolls 16 and 17 are first cast off the platen by depressing the key 22. The record sheet 5 65 is placed on the paper-shelf 14 and moved forward around the under side of the platen between the latter and the feed rolls, and the leading end of the sheet brought up over the sheet-collating table 30, and impaled on the 10 studs 48 with the sheet in position to receive the first line of writing. The impaling studs serve to automatically square the sheet to the writing line and hold the sheet in position while a bill or invoice 66 is arranged on 15 the collating table to overlie the original sheet with a carbon sheet interposed. The invoice sheet is also alined and held in position by the studs 48. When the work-sheets have been thus arranged, the key 22 is 20 pushed up to return the feed rolls to holding position, as shown in Fig. 3, and the key 54 is pressed rearwardly to withdraw the impaling studs to the Fig. 4 position. The two keys may be operated concomitantly by a 25 single motion of the operator's hand. The work-sheets are now free to be advanced over the table 30 by the line-spacing mechanism as the typewriting proceeds.

If desired, the work-sheets may each be 30 impaled by a row of studs along one margin only, and may be of such width that the opposite edge of the sheet does not reach to the opposite row of impaling studs. Thus, for example, the record sheet 65 may have a row 35 of perforations to engage the studs at the table section 32, while the overlying invoice sheet may have perforations along its left-hand margin to receive the studs projecting from the left-hand table section 31. By 40 adjusting the section 31, the position of the invoice sheet relative to the underlying record sheet is adjusted, as may be needed to cause the rulings on the two sheets to register.

45 Variations may be resorted to within the scope of the invention, and portions of the improvements may be used without others.

Having thus described my invention, I claim:

50 1. The combination with a sheet-collating table, of sheet-impaling studs arranged in rows adjacent the side edges of the table, supports or carriers on which said studs are mounted, said carriers hinged to the rear 55 face of said table, the latter provided with openings through which said studs may project into position to enter perforations in the margins of work-sheets arranged on the table, and means to swing said supports to 60 withdraw the impaling studs to an inoperative position, said means comprising a rock shaft extending across said table between said supports, a key to rock said shaft, and rock arms on said shaft connected to swing 65 said supports.

2. The combination with a sheet-collating table, of sheet-impaling studs arranged in rows adjacent the side edges of the table, supports or carriers on which said studs are mounted, said carriers hinged to the rear 70 face of said table, the latter provided with openings through which said studs may project into position to enter perforations in the margins of work-sheets arranged on the table, and means to swing said supports to 75 withdraw the impaling studs to an inoperative position, said table comprising sections relatively adjustable to adjust one row of impaling studs toward and from the other row of studs.

80 3. In a typewriting machine, the combination with a roller platen, of a sheet-collating table at the delivery side of the platen in position to support the leading ends of work-sheets while the latter are on the platen in position to be written upon, said table comprising telescoping or overlapping sections relatively adjustable in a direction lengthwise of the platen, and work-sheet-holding means to engage the side margins of 90 work-sheets on said table, said holding means relatively adjustable with the table sections.

95 4. In a typewriting machine, the combination with a roller platen, of a sheet-collating table at the delivery side of the platen in position to support the leading ends of work-sheets while the latter are on the platen in position to be written upon, said table comprising telescoping or overlapping 100 sections relatively adjustable in a direction lengthwise of the platen, a series of sheet-holding and gaging studs on each of said sections in a position to enter perforations in the side margins of work-sheets arranged 105 on said table, said studs adjustable with the table sections, and means to withdraw said studs as to an inoperative position.

110 5. In a typewriting machine, the combination with a platen frame and a roller platen mounted thereon, of a work-sheet supporting table extending upwardly from the platen in position to support the leading ends of work-sheets as they are advanced beyond the printing line on the platen, said 115 table mounted on the platen frame and having a pivotal connection therewith adjacent one end of the platen, permitting said table to swing upwardly and laterally about an axis perpendicular to the platen axis.

120 6. In a front-strike typewriting machine, the combination with a roller platen and a platen frame, of a work-supporting table extending upwardly and rearwardly from the front face of the platen, and a support 125 carrying said table, said support extending lengthwise of the platen and having a pivotal connection with the platen frame adjacent one end of the platen, and having a releasable connection with the platen frame 130

adjacent the opposite end of the platen, whereby said support and table may be swung upwardly and laterally away from the platen.

- 6 7. In a front-strike typewriting machine, the combination with a roller platen and a platen frame, of a work-supporting table extending upwardly and rearwardly from the front face of the platen, a support carrying
10 said table, said support extending lengthwise of the platen and having a pivotal connection with the platen frame adjacent one end of the platen, and having a releasable connection with the platen frame adjacent
15 the opposite end of the platen, whereby said support and table may be swung upwardly and laterally away from the platen, said table comprising sections relatively adjustable lengthwise of said support, and work-
20 sheet-gaging means carried by said sections.
8. In a typewriting machine, the combination with a roller platen and feed rolls running on said platen, of a key to throw said rolls off the platen, a sheet-collating
25 table at the delivery side of the platen on which work-sheets may be arranged and adjusted while portions of the sheets extend around the platen in engagement with said feed rolls, alining studs arranged to enter
30 perforations in the side margins of the work-sheets while the latter are supported on said table, and a key operable to withdraw said studs to an inoperative position, said last-mentioned key being located adjacent the platen roll release key and arranged
35 to enable both said keys to be actuated by a single movement of the operator's hand, to clamp the collated sheets by means of the rolls at their release from the studs, thereby

preserving the location of the sheets ob- 40 tained by the use of the studs.

9. In a typewriting machine, the combination with a revoluble platen and a releasable paper feed-roll to run thereon, of a sheet-collating table upstanding in front of 45 the platen, a row of impaling pins on said table arranged at different distances from the platen in position to enter marginal perforations along the side margin of a work-sheet arranged on said table, said pins 50 sufficiently near said feed-roll to permit engagement of the work-sheet simultaneously by the feed-roll and the pins, and a key connected to means for stripping the work-sheet from the pins, to permit the work-sheet to 55 be advanced by the platen and feed-roll.

10. In a typewriting machine, the combination with a revoluble platen and a releasable paper feed-roll to run thereon, of a sheet-collating table upstanding in front of 60 the platen, two rows of impaling pins on said table arranged at different distances from the platen in position to enter marginal perforations along the side margin of a work-sheet arranged on said table, one row 65 at each side of said collating table, said pins sufficiently near said feed-roll to permit engagement of the work-sheet simultaneously by the feed-roll and the pins, and a key connected to means for stripping the work-sheet from all of the pins in both rows 70 simultaneously, to permit the work-sheet to be advanced by the platen and feed-roll.
